UNITED STATES PATENT OFFICE.

WILLIAM J. NEIDIG, OF MADISON, WISCONSIN, ASSIGNOR, BY MESNE ASSIGNMENTS,
TO CHICAGO TITLE AND TRUST COMPANY, TRUSTEE, A CORPORATION OF ILLINOIS.

TYPE-WRITING MACHINE.

1,053,925.

Specification of Letters Patent. Patented Feb. 18, 1913.

Application filed April 25, 1910. Serial No. 557,330.

To all whom it may concern:

Be it known that I, WILLIAM J. NEIDIG, a citizen of the United States, residing at Madison, in the county of Dane and State 5 of Wisconsin, have invented certain new and useful Improvements in Type-Writing Machines, of which the following is a specification.

Certain principles and features of my invention as described herein are included 10 within the generic invention which is described and claimed in my co-pending application filed April 20, 1908, Serial No. 428,212.

15 The objects of the invention as the same is more specifically illustrated in the accompanying drawings are, first, to indicate to the operator the distance to the bottom edge of his sheet from the current printing position, and this line by line and automatically, irrespective of the length of the sheet, and beginning a considerable distance from the end of the sheet; second, to give the operator a visual signal upon his nearing the 20 end of the sheet, and this automatically; third, to supply him with a signal, preferably an audible signal, automatically, upon his bringing a predetermined point upon the sheet into the printing position; fourth, to render the machine inoperative upon the 25 completion of his predetermined last line, also automatically; fifth, to release the machine for further printing upon running out the completed sheet, automatically; sixth, to enable the operator to release the 30 inoperative machine for further printing upon the sheet being printed, at will; seventh, to supply certain means adapted to make the invention more effective in its application and use, as hereinafter described; 35 and eighth, to supply certain means adapted to be applied to other sheet-movement-indicating uses of the same general character.

40 There is to-day no device upon the market to tell the operator how near he is to the bottom edge of his sheet until the edge itself comes into sight. I supply him with a practicable system of signals to prevent his over-running his page upon his desired bottom margin. In addition I indicate for him 45 the extent of the unused space left upon the paper sheet, beginning long before the time to remove it, and continuing to the very end, so that he can look ahead and tell 50 whether he has room on his sheet for a

group of matter like a footnote, or a table, or a chapter heading, or the complementary close and signature of a letter, that cannot well be divided, and thus can stop his page in advance of the predetermined page-length if need be, and this without preliminary care on his part. This function has never before been performed, but is novel 60 to my invention.

I attain my several objects by the mechanism illustrated in the accompanying drawings, in which—

Figure 1 is an end view of one embodiment of my invention; Fig. 2 is a detail view of certain parts; Fig. 3 is a top or 70 plan view of certain portions of Fig. 1, with parts broken away to show the mechanism for frictionally connecting my indices with the platen; Fig. 4 is a view similar to Fig. 3, but shows a modification having the frictional connecting mechanism transformed 75 into a lateral clutch mechanism by the locking action of the adjunct latch 115; Fig. 5 is a front view of a portion of Fig. 1, in vertical section on the line B B; the bell 80 signal being omitted. Fig. 6 is a view in vertical cross-section of a portion of Fig. 1; Fig. 7 is an illustration of the toothed friction-disk shown in Fig. 6; Fig. 8 is an edge view of a detail shown in Fig. 1; Fig. 9 is 85 a top view of the same; Fig. 10 is a top or plan view showing mainly the sheet-controlled elements shown in Fig. 1; Fig. 11 is an enlargement in partial cross-section of a detail shown in Fig. 3; Fig. 12 is a top 90 view of a modification of Fig. 3, showing a toothed detaining engagement with the frame 12, instead of a frictional engagement; Fig. 13 and Fig. 14 are like Fig. 12, except that instead of a toothed detaining 95 engagement a stop detaining engagement is used; Fig. 15 is a simplified modification of Fig. 3, some of the elements being omitted; Fig. 16 is likewise a simplified modification, other elements being omitted; Fig. 17 illustrates another form of releasable friction 100 combined with a detaining part on the frame; Fig. 18 shows a still simpler form of releasable lateral friction device; Fig. 19 shows a modification in which the sheet-controlled elements are stationed underneath the platen; Fig. 20 is a front view of the same partly in vertical section; Fig. 21 is an end view, and Fig. 22 a front view partly 105 in vertical section, of another form of sheet- 110

controlled elements, in connection with another means of connecting my indices with the platen; Fig. 23 is a view showing a modification of my sheet-controlled elements; Fig. 24 is a top view of a portion of the same; Fig. 25 is a view showing a still different modification of my sheet controlled elements, and also a modification of the structure carrying the indices, and of the decreasable friction between the indices, and the platen; Fig. 26 is a view of a further modification in the form of my sheet controlled elements; Figs. 27 and 28 are top views of certain parts shown in Figs. 26, 15 and 29; Fig. 29 is a view in section on the line D D of Fig. 26 of the same parts in a second position; Fig. 30 is a view illustrating a further modification in the form of my sheet-controlled elements; Fig. 31 is a dia- 20 grammatical representation of another form of decreasable frictional connection between my indices and the platen, together with a more direct form of sheet-control therefor; Fig. 32 is a view showing my indices differ- 25 ently stationed on a dial and having an adjustable frictional connection with the platen in a still different form; Fig. 33 is a top view of the same with certain parts removed; Fig. 34 is an end view, with the 30 plate 11^b (Fig. 35) removed and the carriage frame and frame extension indicated in dotted outline, of a desirable simplified modification when the full friction-decreas- 35 ing and drum-detaining mechanism shown in Fig. 3 is not required; Fig. 35 is a view in cross section of the same; Fig. 36 is a view in cross-section of a portion of Fig. 37; Fig. 37 is a view of a modification contain- 40 ing a still simpler frictional connection be- tween my indices and the platen; and Fig. 38 represents a portion of a modified form thereof.

Similar symbols of reference refer to similar parts in the several drawings.

45 The embodiments of my invention which are shown and described herein comprise a series of operative indices adapted to indicate progressively within their range the extent of the remaining unused paper and 50 having a connection with the platen that normally causes them to move with the platen but permits them to be detained or stopped independently of the platen, a detaining means to stop them in a suitable 55 initial or starting position, and a releasing means to release them at a constant point in the progress of the bottom edge of the sheet so that they may resume their movement with the platen. Added to these in- 60 dices are various signaling and locking means, together with other accessories intended to make the invention more useful, or more readily applicable to different machines under varying conditions of opera- 65 tion.

The embodiment of my invention shown in Figs. 1 to 11 is described as follows: The carriage frame 12, carried in the usual manner upon the main frame 41 of the type-writing machine, has journaled in its ends 70 the platen arbor 13 as shown, bearing the platen 10, which in practice is connected in usual manner with the usual line spacing mechanism, not shown herein. The usual paper table 8 for the support of the entering sheet is shown, the same being attached in the usual way to the carriage frame 12. 75

I place upon the arbor 13 the friction-disk 11^b, attaching it fixedly to the platen by means of screws 103 (Fig. 6). Against this part 11^b is placed the friction washer 11^a, made preferably of a material like leather, and against the washer is placed another friction-disk 11, shown separately in Fig. 7, supplied upon the outer face there- 80 of with the annular interdental depressions 51. I next mount upon the arbor 13 a composite part consisting of the bushing 42 and the drum 6, the drum being fixedly attached upon the bushing and forming in effect a 85 single piece with it. The drum bears in a peripheral trough the annular band 6^{a,b}, which preferably is made of a material having small inertia, like paper or thin celluloid. This band can be adjustably moved 90 upon the drum, having a frictional connec- 95 tion therewith; and it bears upon its surface indices and certain other markings, as will be hereafter explained. The adjustment provision is intended to add to the use- 100 fulness of the invention, but it is not an es- 105 sential part thereof.

With the drum I combine the following features: The bracket 100, located within the inclosure of the drum and attached to 105 the outward shell-wall thereof by rivets 102, has fastened upon it the radially-disposed shouldered pin 53 by means of the nut 53^a. Journaled upon this pin is the hub 88, from 110 the lower portion of which radiate in differ- 115 ent directions the lever-tooth 52, Figs. 3 and 6, adapted to engage with the interdental depressions 51 in the disk 11, and the tail- 120 lever 54, Fig. 3, engaged by the spring 7, which is more clearly shown in Fig. 11. This spring is attached by one end to the 125 wall of the drum by means of the screw 9' and the adjusting nut 9, Figs. 3 and 11, and it acts through the engagement of the other end with the tail-lever 54 to press or actuate the disk 11 upon washer 11^a and upon disk 11^b, the said parts engaging through friction surfaces thereon so as to give a 130 frictional connection between the drum and the platen. A bend in the intermediate portion of the spring 7 makes contact with the outer wall of the drum, the said wall serving as an abutment from which the spring reacts. By turning the nut 9 the tension of the spring may be changed. Other forms

of spring may be used in securing a frictional connection between my indices and the platen, as for instance any one of the springs shown in Figs. 18, 31, 34, 35, and 38, or a spring may be dispensed with and the friction be secured without it, as shown in Figs. 25, 32, 33, 36 and 37. I do not limit myself with respect to the form of the spring, or with reference to the other means 5 of adjusting the friction to increase or decrease it, and may dispense therewith. The friction may be other than a lateral friction, as shown in Figs. 25, 31, 32, 36, 37 and 38.

The remaining structure within the 10 contour of the drum 6 is described thus: The upper portion of the hub 88 takes the form of the arm or lever 92, bearing the pin 94. Upon this pin 94 is placed the lever 95, one arm of which terminates in the friction-shoe 20 96^a, and the other in the projecting lever-end 14. In order to return this lever 95 into its operative position, I provide the 25 contracting spiral spring 98 having one end thereof engaged with the said lever and the other end attached to one of the walls of the drum, and the lever is formed with the slot 97 to work over the stop-pin 93 on the lever 92, the said spring operating to hold one end of said slot against the said stop-pin with 30 any desired firmness. An opening 76 in the inner wall of the drum permits the play of the projecting parts 52 and 14, while the opening 75 in the outer wall of the drum permits the play of the friction-shoe 96^a and 35 the parts bearing it. To coöperate with the friction-shoe 96^a in a detaining action described later, I place upon the carriage frame 12 the extension 99, bearing the friction-surface 99^a. The washer 173, Fig. 6, on 40 the arbor 13 holds the drum in an operative position laterally.

I attach to the carriage frame 12 by means of the screws 64 the frame extension 22, Figs. 1 and 10, bearing the inwardly projecting axle 20 (see Fig. 10): Upon this axle is journaled the hub or sleeve 21, bearing the fixedly attached lever 74, the fixedly attached piece 59 with its projecting stop-pin 62, the fixedly attached collar 105, and 50 the fixedly attached lug-piece 17. Journaled upon the hub or sleeve so as to turn freely thereon is also the stop or lever 15 with its lug 63, the said lug bearing upwardly against the before-mentioned stop 55 62. This stop or lever 15 is stationed in the plane of the projection 14 (Fig. 3) on the drum 6, and the adjustment of parts is such that it normally projects into the path of the said projection 14, the parts 59 and 105 60 serving to give it suitable lateral position, and the pin 62 supporting it in the suitable angular position, the pin 62 being itself positioned by the spring 111. The purpose of connecting the stop or lever 15 with hub 21 65 in this manner instead of attaching it fix-

edly thereon is to permit of a backing-up movement of the projection 14 when the platen is turned backwardly, as in backing-up the sheet, the stop 15 lifting idly upward out of the way in such a movement, and then returning into position through the force of gravity. I do not limit myself to this particular means of providing for such a backing-up movement of the projection 14 past the stop-lever 15. The stop-lever 15 is 70 adapted to act as a stop upon the projection 14, and it has a distinct lever function as well. Through it the projection 14 controls the position of other parts, and is not merely controlled by them. As I have just explained, the normal position of this lever or stop 15 is in the path of the projection 14, and it is supplied with means returning it into such position. I do not however confine myself in all cases to the use of a stop 75 having any particular special characteristics.

The parts upon the sleeve or hub 21 are 80 returned into operative position by the action chiefly of the spring 111, Figs. 1 and 10, which is attached at one end to the frame 12 by the pin 112 and at the other end engaged with the lever 74, the said lever being normally held against the stop-pin 113 on the frame extension 22 by the pulling action 95 of the spring, and this more or less firmly according as the leverage is increased or diminished by engaging the spring with the lever 74 farther from or nearer to the hub 21. The weight 66 also assists in this returning function. A second function of the 100 spring is to pull backwardly against the action of the projection 14 upon the stop 15, so as to subtract from the pressure upon the sheet. The weight 66 also serves this function. 105

The action of the parts thus far described is controlled by the sheet, through the following structure:—At the end of the sleeve or hub 21, but independently of it, I journal 110 upon the axle 20 a paper-feeler whose end describes an arc intersecting the path taken by the sheet, so that when the sheet is present the paper-feeler cannot complete its movement but is stopped by the sheet, but 115 when the sheet passes on the paper-feeler is left free to complete its movement into a slot 4, Fig. 10, in either a paper-table or a piece applied thereto. The preferable form of this paper-feeler is that shown in Fig. 1, 120 in which the part 28', journaled on the axis 20 and bearing the pin 23 and the stop-pin 24, has journaled upon the said pin 23 the paper-engaging portion 28, the lug 65 thereon engaging against the stop-pin 24 so as to 125 form a one-way flexion means, or knee-joint. The purpose of this joint is to provide for a backing-up movement of the sheet; but it is to be noted that the joint may be omitted; as shown in some of my figures, without affect 130

ing the operativeness of the invention. The eccentric weight 66 is connected with the paper-feeler in order to return the latter into the most convenient operative position, 5 out of the way of the entering sheet, as shown in Fig. 1. The paper-feeler is operatively connected with the stop or lever 15 through the stop-pin 36, Fig. 10, on the said weight, and the lug 17 on the hub 21. The 10 essential features of this portion of the mechanism are the paper-feeler, its axis, and the lever or stop 15. It is possible to omit the intermediate stop-lever 15 and the separate axis 20, by placing the paper-feeler 15 upon the same axis with the platen and giving it a path intersecting the path of the paper sheet direct, as shown in Fig. 31. I do not regard my invention as limited to any particular form or forms of paper- 20 feeler, nor to any particular position therefor, nor to any particular manner of connecting the paper-feeler to act controllingly upon the indicating means employed.

In order that the paper-feeler may move 25 in a path intersecting the path taken by the sheet in cases in which the invention is applied to machines in which the paper-table 8 is unprovided with the slot 4 shown in Fig. 10, I attach upon the paper-table 8 the 30 piece 8', Figs. 1, 8 and 9, containing the slot 4. This piece is shaped to hook around the rear edge of the paper-table, and its slotted portion lies upon the paper-table as indicated in Fig. 1. The piece 8' is secured in 35 place upon the paper-table by means of the set-screw 80. Other forms of slotted plates or auxiliary paper-backing that may be used with suitable forms of paper-feelers in such cases are illustrated at 8², Figs. 26, 28, 40 29, and at 8⁴, Fig. 30, described later. I do not limit myself to any particular manner of providing for the action of the paper-feeler into the paper-path. The paper-feeler can be made to operate from underneath the 45 sheet just as well, as illustrated in some of my figures.

The mechanism described automatically brings the paper-feeler into an operative position permitting the introduction of the 50 sheet, without interference, a function that I believe no signaling mechanism employing a paper-feeler in connection with typewriting operations has before performed, but that is novel to my invention. My backing-up provision is novel also.

The action of the structure thus far described is as follows: The sheet of paper 45 is entered into the machine in the usual way down the paper-table 8, advanced in 55 usual manner into printing position, and printed line by line as usual, the platen carrying forward the sheet in the usual and well-known way. As the drum 6 is connected frictionally with the platen, at 60 first it rotates step by step also. Eventually

however the projection 14 meets the lever 15 in its path. At first it pushes this lever idly ahead of it, imparting a turning movement to the hub or sleeve 21 and moving the paper-feeler 28 in the arc 101, Fig. 1. 70 It will be seen that if the paper sheet were not present, the end of the paper-feeler would continue on into slot 4 until the projection 14 cleared the lever 15, and the drum 6 would continue its movement with 75 the platen. But during the presence of the paper sheet over slot 4 the paper-feeler cannot thus enter the slot, but is stopped by the sheet. The lever 15 thereupon becomes a detaining stop in the path of the projection 14. By this time the friction-shoe 96^a has been carried forward opposite the part 99 on the carriage frame. A further movement forward of the frictionally connected drum 6 must result in a turning of 80 the lever 95 upon the pin 94, thus driving out the shoe 96^a against the friction-surface 99^a. The resultant friction will at once act detainingly upon the drum, so that thereafter less force than before will be required 85 to stop the drum against the forces tending to rotate it. The stop 15 will also act detainingly upon the drum. But meanwhile another action is taking place, the pressure of the shoe 96^a against the part 99 under the 90 leverage of projection 14 resulting in an inward pressure upon the end of lever 92, thereby opening up or easing the friction between the drum and the platen against the action of spring 7. That is to say, the 95 friction between drum 6 and the platen is regulated under the control of the sheet, varying accordingly as pressure is exerted upon projection 14 by stop 15, such pressure being increased to a controlling extent during the control by the sheet of paper-feeler 28. These agencies acting together are calculated to detain the drum with the minimum of pressure against stop 15 and consequently against the sheet, and that is my 100 purpose in using all of them. And as the spring 111 acting upon the lever 74 adds still another means of subtracting from the pressure of the paper-feeler against the sheet, I have a mechanism adjustable with 105 the greatest delicacy and sureness to any conditions of service that may arise. My drum is now detained or stopped, and it will always be stopped, necessarily, with the same point on its periphery opposite the 110 pointer 34. This point may be indicated by the small circle or index 89. In this position it remains during the presence of the sheet. Eventually, however, the sheet is advanced until the bottom edge thereof 115 passes the paper-feeler 28. Instantly the paper-feeler enters slot 4, stop 15 ceases to act detainingly upon projection 14, shoe 96^a is withdrawn by spring 98 from contact with the controlling part 99, and the 120

friction between the platen and drum 6, spring-actuated by spring 7, and no longer controlled or regulated by the sheet, becomes of its original force, insuring the simultaneous rotation of the drum with the platen. It is clear that as the sheet is further advanced, drum 6 will be advanced coördinately therewith, and that symbol 89 will be advanced away from 5 pointer or index 34 and another peripheral point be brought opposite it. This point can be marked to indicate the distance remaining from the printing point to the end of the sheet, or to a point a fixed distance therefrom. That is to say, if the end of the sheet 10 is seventeen line-spaces distant from the printing point at this moment, I can mark my periphery 17 to indicate this distance, and after another advance I can mark the new point on the periphery 16 to indicate 15 the new position of the sheet-end relative to the printing point, if the distance be sixteen line-spaces, and so on during the remaining progress of the sheet. I prefer to use indices involving no mental calculation nor 20 memorizing on the part of the operator, such as the series of descending numerals shown, and I prefer to use the line-space as a unit of measurement, but my invention is not dependent upon the use of any 25 particular kind or number or order of indices.

It is to be noted that the mechanism described can be backed-up from any position 30 of the sheet and to any required extent; the knuckle-joint construction of the paper-feeler and the one-way stop provision in connection with stop-lever 15 permitting 35 free backing-up of both sheet and drum.

Adjuncts.—The mechanism described can 40 be used upon the most delicate tissue fabrics without danger of injury. A mechanism of such delicacy of adjustment will not always be needed, and indeed upon cer-

tain classes of work could not be used to the 45 best advantage. For the purpose of simplifying the action of the mechanism I desire to show means whereby certain of the elements shown as coöperating may in effect be 50 eliminated, and the mechanism used without them, and this at will. To this end I place upon the outside wall of the drum the lock-piece 16, Fig. 3, shown by dotted lines in Fig. 1, pivoting the same stiffly 55 upon the pin 18 in such wise that it will retain any position given it. This piece when moved toward the periphery of the drum lies away from the lever-end 14, but when shifted toward the arbor of the drum it lies 60 against the said lever and locks it, thus preventing the action of the levers within the drum. When thus locked the projecting lever-end 14 acts as a fixed projection carried by the drum, and the connection be- 65 tween the drum and the platen is a simple

frictional connection. The action is the same essentially, the difference being that there is no easing of the friction between the platen and the drum, and no coöperation of the part 99 in detaining the drum, the entire work of detaining the drum falling upon the lever 15. I show modifications of this simpler combination of elements in certain of my figures. I also wish to provide means whereby the operator may at will secure a more positive connection with the platen, as for instance when the signaling or locking mechanism requires greater power to operate than is afforded by the frictional connection, or when for other reasons a more positive connection with the platen is desirable. To that end I supply the periphery of the disk 11 with one or more pivoted latches 115, the same being pivoted at one end upon the pin 116, and at the other end 70 having a projection adapted to fit into the depressions 117 in the periphery of the disk 11^b. These latches are made preferably of a resilient material, and are shaped conveniently for manipulation. Their purpose is to furnish a means of locking the disks 11 and 11^b together so that they will turn as a unit. When this is done, as shown in Fig. 4, the frictional connection between the platen and the drum 6 is in effect eliminated. As the tooth 52 is able to lift entirely free of the interdental spaces 51, and under the pressure of the lever 95 upon the lever 92 will always so lift free when the said disks are locked together and the lever-end 14 is pressed against by the obstructing stop 15, I have instead of an easable frictional connection a releasable lateral toothed clutch connection between the drum and the platen. The lock-piece 16 in this use 75

must of course be shifted aside so as not to interfere with the action of the lever 95.

Other indicating means.—In connection with my indices I employ certain signaling and locking devices to notify the operator 80 of the approach of the bottom edge of the sheet and to prevent his running over upon his predetermined bottom margin.

My visual signal is given thus: I divide the periphery of the part 6^{ab} into two portions as shown, the one being supplied with the indices 6^a, and the other, 6^b, preferably remaining blank. I color these two peripheral sections in such a manner as to form a striking contrast one with the other, the one 85 preferably being colored white with black indices thereon, and the other, 6^b, preferably being colored a solid black. By attaching the combined shield and pointer 34 as shown, I conceal the section bearing the indices 6^a 90 from the eye of the operator during its period of rest, and then bring it into sight, along with the indices. This furnishes me with a very perfect signaling means, the striking change from black to white being 95

well adapted to attract the operator's attention and warn him of the advanced position of his sheet.

My audible signal is given thus: I journal in the end of the carriage frame 12 the short shaft 70, bearing fixedly attached upon its inner end the trip-lever 69, and upon its outer end the loosely-fitted striker-stem 72 and the fixedly attached lever 61, upon which is the inwardly-projecting pin 71, so arranged as to bear against the stem 72 and lift it when the trip-lever 69 is pressed in one direction, but to fall idly away from it when the trip-lever is pressed in the other direction. The stem 72 bears at its end the hammer 26, adapted to strike against the bell 27, the said bell being supported upon the carriage frame 12 by the central pin 86. The drum 6 is supplied adjustably with the outwardly-projecting pin 68, into the orbital path of which the trip-lever 69 before mentioned projects. The adjusting means are these: I supply the drum 6 with a series of threaded seats 67, arranged preferably at line-space intervals circularly around the axis 13, into any of which the pin 68 may be screwed; and according as I place it in one or the other of them my signal is given when the end of the sheet is in one position or another. The lettering 177 placed opposite these seats is intended to guide the operator in making his adjustments. Other means of adjustment are possible. The purpose of the lever 61 and pin 71 is to permit of a backing-up movement of the pin 68. When it is time for the bell signal to be given, the pin 68 presses against the lever 69, thus rocking the shaft 70 together with the lever 61, and through the pin 71 raising the hammer 26 from the bell. The pin then passes on, the lever 69 is released, and the bell-hammer 26 falls against the bell, causing it to sound.

The means whereby I render the printing instrumentalities of the machine incapable of doing further printing upon the sheet are described as follows: I place upon the end of the carriage frame 12 the inwardly-projecting pin 37, having journaled thereto on the end of the rocking bail-piece 3. This bail-piece extends the entire length of the platen and lies parallel to the axis thereof; and its further end is similarly journaled upon a pin 37 in the further end of the carriage frame 12, these parts being similar in form to the parts shown. Coöoperating with this bail-piece is the plate 46 journaled upon the pin 47, the said pin being carried upon an upwardly-extending arm of the piece 49, which is shown as passing through the machine from one end to the other parallel with the platen axis, and attached at either end to the main frame 41 by the screws or bolts 77. The plate 46 bears a lever arm 48, upon which is stationed the

projecting pin 50. The plate is so balanced as normally to lie in position as shown in Fig. 5, away from the printing point. The type-bar 78 is carried upon the axis 80 in the usual way, and the printing type 73 at its head swings in the usual way in the orbit 79 to deliver the printing stroke, the printing point being indicated by the mark 44 in Fig. 5. I place upon the carriage frame 12 the frame extension 2, upon which is the inwardly-projecting pin 174. Journaled upon this pin is the trip-lever 1, the lever 19, and the weight 176, the three constituting a single piece. The lever 1 lies in the path of the pin 68 and is operated by it; the lever 19 cooperates with the pin 175 projecting outwardly from the end of the bail-piece 3 into its path; and the weight is used to restore these levers to their operative position.

When it is time to render the printing mechanism incapable of printing further upon the sheet, the pin 68 presses against the trip-lever 1, the lever 19 through the pin 175 rocks the bail-piece 3 upward on its axis, and the bail-piece through the pin 50 shifts the plate 46 until it lies in the path of the type 73 over the printing point 44. If now the operator attempts to print an additional line upon his sheet he is unable to do so, for the type strike upon the plate 46 and do not meet the paper. The operator thereupon removes his sheet by turning his platen forward, the pin 68 passes the lever 1, the bail-piece 3 falls, and the plate 46 uncovers the printing point, rendering the machine again operative. If however the operator wishes to print an additional line upon his sheet he has only to turn his platen forward a line or so and then backward and his machine is released for further printing to any extent.

Fig. 12 is a view of another arrangement of parts from that shown in Fig. 3 the structure being the same except that slot 97 and stop-pin 93 are omitted and instead of the retractable friction-shoe 96^a the retractable tooth 96^b is used, and instead of the coöperating friction-surface 99^a on the part 99, the coöperating teeth 99^b. In this modification the pressure of the lever-end 14 does not tend to open the frictional disks 11 and 11^b, but the frictional driving action impelling the drum forward itself tends to open the friction through what is in effect the pulling action of the pin 94 upon the lever 92.

Fig. 13 is like Fig. 12 in structure and action, except that instead of the retractable tooth 96^b the retractable stop 96^c is used, and instead of supplying the part 99 with the coöperating teeth 99^b I supply it with the coöperating stop 99^c.

Fig. 14 is like Fig. 13 in structure, except that I substitute for the lever 95 and re-

tractable stop 96^c the lever 95^a having the stop 96^e, and instead of bringing my levers into action primarily through the coöperation of the lever 15 with the projecting lever-end 14^a, the primary action is the action of the stop 99^c upon the stop-lever 95^a, 96^e. This action pushes the projecting lever-end 14^a against the lever 15 until the paper-feeler 28 is stopped by the sheet; after 10 which the detaining and opening action of the modification is like that of Figs. 12 and 13.

Fig. 15 is a view showing how the lever 95, together with the detaining part thereon 15 and the coöperating part 99 on the frame, may be omitted, the lever 92^b itself being shaped to form the projection 14^b. In this modification the lever 15 acts more directly upon the projecting lever-end 14^b to open 20 the friction between the disks 11 and 11^b and to detain the drum 6.

Fig. 16 is like Fig. 15 in structure, except that the frictional connection with the platen is eliminated (as in Fig. 4, in effect), 25 the connection between the drum and the platen being a releasable lateral toothed clutch connection without the use of friction surfaces.

Fig. 17 is a view showing how the lever 95^c may be used alone to perform the work of opening the friction and detaining the drum, the lever 92 being omitted. In this modification the coöperating part 99 on the frame is retained, but changed slightly in 35 form. The spring for the friction is changed also in form. Part of the structure involved is shown in cross-section in Fig. 18. The armed dished spring 7' holds the drum frictionally against the friction-disk 11^b 40 through the agency of the sleeve-washer 106, upon which the drum is journaled to turn freely. The pressure of such a spring can be adjusted if desired by means of the washer 107; a simple substitution of a 45 thicker or thinner washer will accomplish this adjustment. The lever 95^c is attached to the drum by means of the axis pin 94 in a manner similar to that already described. This lever terminates in a friction-shoe 96^d, adapted to coöperate with the friction-surface 99^d on the part 99. The action is as follows: The projecting lever-end 14^s, 50 pressed upon in effect by the lever 15, operates the lever 95^c so that the part 96^d pushes inwardly upon the outer surface 99^d of the part 99, which action has both a detaining effect upon the drum and also an opening effect upon its frictional connection with the platen, the drum being pulled outwardly 55 away from the friction-disk 11^b by the leverage exerted upon the pin 94. In other respects the action of this modification is the same as has been described.

Fig. 18 is like Fig. 17 in every respect, except that all the levers within the drum are

dispensed with, and likewise the coöperating part 99 on the frame. The drum is detained and the friction opened by the simple coöperating action of the projection 14^c, now fixedly attached to the drum, and the lever 15, the projection having a beveled working face 31, and the lever 15 a beveled working face 30. The action of these beveled faces tends to push the drum outwardly from the friction-disk 11^b, thus opening the friction, 75 and at the same time a detaining action upon the drum is exerted. In this respect the modified mechanism is the equivalent of portions of the mechanism already described. It is possible to omit the beveled faces from this modification, in which case the co-action would be merely a stopping action, like that of Fig. 1 when the projection 14 is locked by the latch 16, with no easing of the friction, the omitted elements in this case corresponding to the eliminated elements in that.

In Figs. 19 and 20 the arrangement of parts is like that shown in Fig. 1, except in the sheet-controlled elements, some of which, 90 shown in Fig. 1 are here omitted, and the remainder of which are stationed under the platen instead of over the paper table. The frame extension 22^a bears the inwardly projecting axle 20^a with its hub 21^a. Upon the hub are stationed the fixedly attached lever 15^a, the fixedly attached paper-feeler 28^a, and the fixedly attached weight 66^a. The platen is supplied with the circumferential slot or groove 4' near the end, just beyond the working surface. The paper sheet overlaps this slot, and, upon the passing of the end thereof the paper-feeler enters it, the function of the slot being exactly that of the slot 4 in Fig. 1. And when the projection 14 clears the lever 15^a, the parts automatically return into operative position, under the influence of the weight. A backing-up movement of the projection 14 results in an idle turning backward of the hub 21^a upon the axle 20^a in this arrangement, so that certain one-way flexion means shown in some of my other figures are not needed.

In Figs. 21 and 22 the freely revoluble drum 6 bears the peripheral indices 6^a and the other signaling markings as before described; and it bears also the weight 25, adapted to bring the indices into a suitable starting position when the drum is released from connection with the platen. At a moment determined by the paper-feeler 28^b this drum is connected to rotate with the platen. The paper-feeler here is provided as before with a one-way flexion means, so that it will push idly backward before a backing-up bottom edge of the sheet through and out of the slot 4 in the paper table 8, without disturbing the position of the arm 119^b bearing it. The structure is as follows: Journaled in the frame-extension 124 upon the 115 120 125 130

frame 12 is the axle 125, having fixedly attached thereto at one end the lever 126, and fixedly attached at the other the thumb-lever 118 and the arm 119^b. The lever 126 carries the pin 128, upon which is journaled the friction-roller 127 adapted to make contact with the outer side of drum 6. The arm 119^b carries the stop-pin 24^b, and the paper-feeler 28^b which is hung on the pin 23^b and the movements of which are limited in one direction by the stop-pin. It also carries the pin 121, upon which is journaled the eccentrically balanced or weighted piece 122 having a segmental periphery 123 adapted 10 to rest upon the surface of the platen. When a sheet is to be entered into the machine the operator presses downward upon the lever 118, thus raising the paper-feeler 28^b from its slot and raising also the arm 126 bearing 15 the friction-roller 127. The result is that the drum 6 is released from its frictional connection with the platen. By this action the piece 122 is also lifted clear and falls 20 into position as shown. The operator can 25 at once release the thumb-lever, for the piece 122 will now rest with its periphery upon the surface of the platen and hold the paper-feeler sufficiently clear of the paper table to permit of the easy introduction of 30 the sheet. The sheet is now inserted, the platen turned forward, and, the end of the segment 123 being reached, the paper-feeler will be lowered upon the sheet, which thereafter controls the position of the parts involved. When the end of the sheet passes 35 from under the paper-feeler the arm 119^b is lowered, thereby pressing the friction-roller 127 against the drum 6 in such a manner as to force the drum against the friction-washer 11^a at the end of the platen, thus 40 connecting the drum with the platen. From now on the action of the indices 6^a will be as has been described. In this figure I show indices intended to indicate the distance to 45 the bottom line of a page that ends (say) five lines from the bottom edge of the sheet, instead of to the bottom edge itself.

Figs. 23 and 24 illustrate another arrangement of my sheet-controlled elements, the 50 indices and their connection with the platen being that shown in Fig. 1, but the paper-feeler 28^c being stationed to work from underneath the sheet upward, instead of from above the sheet downward. The structure 55 is this: The frame extension 136 bears the inwardly projecting axle 20^c, and also the inwardly projecting plate 8^c, the plate lying above the paper table 8 at a distance convenient for the ready insertion of the paper 60 sheet between the two, and containing the slot or opening 4^c. The axle 20^c has journaled upon it the hub 21^c bearing the fixedly attached lever or arm 119^c, which is stationed to play past the end of the paper 65 table 8, and in its normal depressed position

rests upon a fixed stop-pin 134. This arm in turn bears the inwardly projecting pin 23^c, upon which is mounted sleeve 21^c carrying the paper-feeler 28^c and the weight 66^c to restore the paper-feeler to operative position, the two being attached the one to the other. To limit the movement of the paper-feeler in the one direction, the arm 119^c bears the inwardly-projecting stop-pin 24^c, against which the weight 66^c engages, 70 the purpose of the arrangement being as before to furnish the paper-feeler with a one-way flexion means for use in a backing-up movement of the sheet. As before, the lever 15^c is loosely journaled upon the hub 80 21^c; and it is provided with the lug 63^c to engage against a second stop-pin 62^c on the arm 119^c, the purpose whereof is to provide it with a one-way flexion means so that the projection 14 may be backed up past it, the 85 lever 15^c lifting idly backward in such an action. The hub 21^c bears also the fixedly attached lever 74^c, and the frame 12 the inwardly-projecting pin 112^c, between which the spring 111^c exerts an adjustable pulling 90 action, in order to counteract more or less completely the weight of the lever 119^c, and its attached parts and in this way to regulate the pressure of the paper-feeler upon the sheet. The paper table 8 contains the opening 133, through which the paper-feeler 28^c may play against the sheet, and when the sheet passes on, into the slot 4^c in the plate 8^c, above the sheet.

In Fig. 25 my indices are carried upon a 100 belt 6^e running over the driving pulley 11^e attached to the platen, and a second pulley 153, the belt having upon it the projection 14^e to coöperate with the lever 15^e, and through it with the paper-feeler 28^e. The 105 lever 15^e is supplied with the weight 146 to restore it into operative position, and with the pin 63^e to engage upon the arm 147 in a one-way flexion means. The indices 6^a may be duplicated upon the belt if desired, and the projection 14^e duplicated, as shown, for use in printing small work. The sheet-controlled elements are described thus: The frame extension 22^e bears the axle 20^e fixedly attached to which are the crank-lever 115 150 and the paper-feeler 28^e. The rod 149 furnishes a connecting means with the lever 15^e as shown, in consequence of being connected at its upper end to the arm 150 and at its lower end to pin 148 carried by arm 147. The action of the paper-feeler is substantially as before described, except that instead of swinging in a direction opposite to that of the paper sheet as in Fig. 1 it swings in a direction following the sheet as in 125 Fig. 19. It is to be noted that I omit the one-way flexion means for the paper-feeler in this arrangement, and that the paper-feeler is retracted from the paper-path by the counter-balancing weight of the rod 149 130

and the arms 147 and 150, instead of by the weight 66. It is to be noted also that in this arrangement the friction between the indices and the platen is a belt friction, that is to say, a peripheral friction, the pulley 11² and the belt 6⁶ being the friction members, and what is more, that it is an easable friction, since if the belt is slack the stopping action of the lever 15^e upon the projection 14^e will at the same time tend to open the friction.

Figs. 26, 27, 28 and 29 illustrate another modification in my sheet-controlled elements, the indices being carried and connected as shown in Fig. 1, upon the frictionally-connected drum 6. In this modification the paper-feeler 28^f is shaped to lie flat upon the paper table under the paper sheet as a turned-in extension of the arm 119^f, and the mask or plate 8² has a slot 4^f shaped as shown in Fig. 28 to receive it. Figs. 27 and 28 show these parts, and Fig. 29 is a view in section on the line D D showing them in the position they assume after the passage of the sheet and before their return into first position. The secondary axis 28^c, stop 24^c and weight 66^c of Figs. 23 and 24 are omitted, as is the opening 133 in the paper table. In other respects the structure is essentially the same as that shown in Fig. 23, the paper-feeler returning automatically by its own weight into first position when the projection 14 clears the lever or stop 15^f, and this first position being such as not to interfere with the entering sheet or lie in the way of the operator manipulating it.

Fig. 30 is somewhat like Fig. 26 in structure, except that I add elements adapted to raise and lower the plate 8^g from and against the paper table, instead of allowing it to remain stationary. The structure is described as follows: The frame extension 142 attached upon the carriage frame 12 bears the inwardly-projecting pin 144, upon which is journaled the arm 119^g, with its turned-in paper-feeler 28^g. It also bears the inwardly-projecting pin 141, upon which is journaled the lever 139, the said lever being supplied with the slot 140, the pin 20^g, and the stop 62^g. Journaled upon this pin 20^g is the piece 15^g, bearing through the lug 63^g upon the said stop 62^g so as to form in effect an operative extension of the lever 139 when its free end is acted upon downwardly, but when such end is acted upon upwardly lifting idly aside, the purpose of this structure being to provide for a backing-up movement of the projection 14, in whose path the piece 15^g normally lies. The lever 119^g bears the pin 143, upon which is journaled the lever 137. This last-named lever carries the pin 138 working in the slot 140; and it bears the turned-in plate 8^g, supplied with a feeler-receiving slot or opening. A spring 111^g engaged by one end

with the pin 112^g pulls downwardly upon the lever 139 as shown, in order to restore the working parts to their operative position. The action of this mechanism is as follows: The sheet 45 is inserted upon the paper table 8, the paper-feeler 28^g meanwhile lying flat upon the paper table underneath it. The sheet is advanced, by rotating the platen and eventually the projection 14 presses against the piece 15^g, thereby lowering the plate 8^g upon the sheet. Further pressure upon the piece 15^g tends to raise the paper-feeler 28^g against the sheet. When the sheet passes on the paper-feeler passes into the slot in the plate 8^g as before, these parts being shaped as shown in Figs. 27, 28 and 29, releasing the lever 15^g from its stopping action. The mechanism now enters upon its indicating action, substantially as described in connection with Fig. 1.

Fig. 31 is a modification showing how it is possible to omit all the sheet-controlled group of elements except the paper-feeler itself and the cooperating slotted paper table; and it also somewhat diagrammatically illustrates a modification in the form of easable or releasable frictional connection between the indices and the platen. The disk or pulley 56, attached to turn as a unit with the platen, has extended around its periphery the friction-strap 57, attached at either end to the pins 60 upon the lever 32. This lever is journaled upon the pin 53^h on the drum 6; and it is provided with a tail 54^h, against which presses the spring 55^h, also attached to the drum 6, the pressure of the spring tending to tighten the strap upon the periphery of the part 56. The lever 32 bears upon its extremity the inwardly-projecting paper-feeler 28^h, in the path 101 of which lies the slot or opening 4^h, in the paper table 8. The sheet prevents the orbitally-moving paper-feeler from entering the slot 4^h, during its presence over the slot, thus detaining the drum, but in this case having fewer intermediate elements to work through. Its action is this: The lever 32, in effect pressed backwardly upon its axis 53^h, loosens the friction-strap 57, opening the frictional connection between the drum and the platen and permitting the drum to stop independently of the platen; and at the same time the paper sheet acts, through the paper-feeler, as a stopping agent, as it would do if the friction were not supplied with an easing means. When the sheet passes on, the lever 32 is released, the friction-strap 57 is tightened by the spring 55^h, and the platen picks up the drum 6 with its indices as before. It is to be noted that in this arrangement the paper-feeler is returned into operative position automatically, and is removed out of the way of the entering sheet automatically.

Figs. 32 and 33 illustrate a modification

showing how my indices 6^a may take dial form and be stationed more conspicuously upon the machine at some distance from the controlling elements. The frictional connection with the platen in this case is effected by means of the platen-connected periphery 11^i , the dial-connected drum 167 , and the cord 135 frictionally connecting the two, belt-wise and guided by the intermediate located pulleys 156 and 166 . The projection 14^i connected with the indices, as before, is engaged by the lever 15^i , which, through the shaft 20^i , crank-arm 148^i , and the rod 149^i , pin 151^i and arm 150^i , is connected with the paper-feeler 28^i and controlled by it. The combined pointer and shield 34^i shown in Fig. 33 but omitted from Fig. 32, permits of a signaling action as well as an indicating action, the two sections 20 of the dial, 6^a and 6^b , being differently colored so as to supply a visual signal. The action of the mechanism is essentially the same as has been described, though as compared with Fig. 1 the friction-producing spring is omitted, and the friction-opening or easing means are omitted, together with certain adjuncts.

Figs. 34 and 35 represent a desirable simplified form of my mechanism, the elements employed being substantially those represented in Fig. 1, except for differences in form and proportion, and except for certain omissions, such as the friction-opening or easing elements, the coöperating detaining element on the frame, and the adjustable element pulling backwardly against the action of the lever 15 to ease the pressure upon the sheet, as well as other elements as will appear. The structure is as follows: The drum 6^k , reduced to a mere peripheral shell having a light friction-flange, carries the indices and signaling markings, and also the projection 14^k . On either side of the flange I place the friction-disk 11^a and 11^b , and against the disk 11^b the armed dish-spring 7^k , and against the spring the circular head-piece 11^b having in the hub thereof the set-screw 83 . These parts are adapted to fit over the platen arbor 13 as shown, so as to be attached against the end of the platen by the set-screw; and they are fastened together by the three screws 9^2 in such wise that the spring pressure upon the friction-flange of the drum 6^k can be increased or diminished. This pressure need not however to be adjustable. Upon frame-extension 22 of Fig. 1, I place the inwardly-projecting axle 20 , having journaled thereon the paper-feeler 28 provided with one-way flexion means as shown in Fig. 1. Also journaled upon this axle is the eccentric weight 66 having thereon the stop-pin 62 and acting as a unit with the piece $28'$ of the one-way flexion means before mentioned, and the lever 15 having thereon the lug 63

to engage against the said stop-pin. The paper table 8 is provided with the slot or opening 4 , through which the paper-feeler may pass. It is to be noted that by using a light drum as shown, light friction, and a shorter lever 15 , the pressure of the paper-finger upon the sheet is decreased until it is sufficiently light for ordinary work, without the addition of the omitted elements. The action of this modification is substantially that of the mechanism shown in Fig. 1 after the projecting lever-end 14 has been locked by the latch 16 .

Figs. 36 and 37 illustrate a still further modification in the friction between the indices and the platen, the spring governing the friction being omitted and the friction being peripheral instead of lateral. The indices 6^a here are carried on a loosely fitted band 6^m of a light material having small inertia, like paper, the band fitting in the peripheral trough of the drum 11^m , which is fixedly attached to turn with the platen. Attached to this band is the projection 14^m , preferably extending out on both sides of the drum to avoid any twisting action when detained. The lever 15^m in such a case would be doubled, as shown, so as to act upon both ends of the projection 14^m at once. The remaining parts are like those in Fig. 34, and the action is the same.

Fig. 38 illustrates a modification as compared with Fig. 37 of the part bearing the indices, which are here borne upon a band 6° made of a resilient material, say a metal spring, adapted to press peripherally, that is to say claspingly, upon the drum 11^m . This band is not continuous, but has two ends, and it has attached to it the projection 14° as shown. The structure otherwise is the same as that of Fig. 37, and the action is the same, except that there is an opening action as well as a stopping action, the pressure of the lever 15 upon the projection 14° tending to open the friction.

It is to be noted that the signaling and locking means illustrated in Fig. 1 may be used in connection with the modifications shown, and that other portions of the fuller mechanism may be used with the various modifications, as will be understood.

The devices shown in the drawings and described herein are part of a series of closely related inventions or improvements which are presented in a number of co-pending applications for Letters Patent filed by me. The said devices have a number of general objects in common with those forming the subject matter of different applications in the said series, and to a certain extent embody and utilize various principles and features which are common to devices shown and described in one or another of the said applications. Some of the said common principles and features are claimed broadly

in my application filed April 20, 1908, aforesaid, and in my applications filed June 15, 1908, Serial No. 438,577; Dec. 13, 1909, Serial No. 532,928; Dec. 15, 1909, Serial No. 533,309; Dec. 16, 1909, Serial No. 533,355; Dec. 22, 1909, Serial No. 534,559; Mar. 30, 1912, Serial No. 687,468; April 4, 1912, Serial No. 688,358; and April 9, 1912, Serial No. 689,560. The branch of the general invention that is covered hereby is distinguished by the characteristic features which are specified in the following claims.

Having thus clearly explained the nature and objects of my invention, and the manner of applying it, I claim as new and desire to secure by Letters Patent—

1. In a typewriting machine, in combination, a platen, an index-carrier and its indices, frictional actuating means having engagement through spring-pressure for giving the said index-carrier simultaneous movement with the platen, and sheet-controlled means for controlling the said movement.

2. In a typewriting machine, in combination, a platen, an operative member having a spring-pressed frictional connection with the platen, visual signaling means called into operation through said member, and sheet-controlled means for controlling the movement of said member with the platen.

3. In a typewriting machine, in combination, a platen, an operative member, indicating means called into operation through said member, frictional actuating means for giving said member movement with the platen, including a spring for holding the friction surfaces thereof in engagement, and sheet-controlled means for controlling the movement of said member.

4. In a typewriting machine, in combination, a platen, a series of indices frictionally connected therewith, and sheet-controlled means to detain the indices and ease the friction and to release the indices and restore the friction.

5. In a typewriting machine, in combination, a platen, an index-carrier, and a sheet-controlled friction-clutch mechanism between said carrier and the platen.

6. In a typewriting machine, in combination, a platen, an operative member, indicating means called into operation through said member, and a sheet-controlled friction-clutch mechanism for connecting said member to move simultaneously with the platen.

7. In a typewriting machine, in combination, a platen, a carrier bearing indices, means including a spring-closed friction-clutch for giving the said carrier movement with the platen, a movable stop for controlling the action of the said clutch, and a paper-feeler for controlling the action of the said stop.

8. In a typewriting machine, in combination, an operative member, indicating means called into operation through said member, means including a spring-closed friction-clutch for giving said member simultaneous movement with the platen, a movable stop for detaining said member and relaxing said clutch, and a paper-feeler connected to control the action of said stop. 70

9. In a typewriting machine, in combination, a platen, a series of indices, means for operatively connecting said series with the platen, embracing friction-members relatively movable laterally, and sheet-controlled means adapted to detain the indices 80 and relax the interengagement of the friction-members and to release said indices and restore the friction. 75

10. In a typewriting machine, in combination, a platen, a series of operative indices, and a sheet-controlled mechanism having laterally-engaging clutch-members for connecting the indices with the platen. 85

11. In a typewriting machine, in combination, a platen, indicating means, and laterally-engaging clutch-devices, convertible at will from friction to positive, and vice versa, for operatively connecting the indicating means with the platen. 90

12. In a typewriting machine, in combination, a platen, indicating means, and laterally-engaging toothed and frictional clutch-devices for operatively connecting the indicating means with the platen and selectively operable to actuate the indicating means 100 either positively or frictionally at will. 95

13. In a typewriting machine, in combination, a platen, an operative member, indicating means called into operation through said member, and a sheet-controlled toothed clutch mechanism, embracing laterally-engaging clutch-members, for connecting the operative member with the platen. 105

14. In a typewriting machine, in combination, a platen, an operative member, indicating means called into operation through said member, means including a laterally closing friction-clutch for giving said member simultaneous movement with the platen, a stop for controlling the movement of said member through said clutch, and a paper-feeler connected to control the action of said stop. 110

15. In a typewriting machine, in combination, a platen, an operative member, indicating means called into operation through said member, means including a friction-clutch having spring-pressed lateral closure for giving said member simultaneous movement with the platen, a friction-controlling member, and a paper-feeler connected to control the action of the last-named member and through it the movement of the operative member. 120

16. In a typewriting machine, in combination, 130

- tion, a platen, an operative member having frictional connection therewith, means controlled by said member for giving an audible signal, and sheet-controlled detaining means for controlling the movement of said member.
17. In a typewriting machine, in combination, a platen, an operative member, a bell-striking means called into operation through said member, frictional actuating means having spring-pressed axial closure for giving said operative member movement, and sheet-controlled means for controlling said movement.
18. In a typewriting machine, in combination, a platen, an operative member, sheet-controlled means including a friction-clutch mechanism for giving said member movement with the platen, and an audible signaling device called into operation through said operative member.
19. In combination, typewriter mechanism including a platen, an operative member, frictional actuating means for giving said member movement with the platen, sheet-controlled means for controlling said movement, and means controlled by the operative member for preventing the use of a part or parts of the typewriter mechanism.
20. In combination, typewriter mechanism including a platen, an operative member, means including a friction-clutch mechanism for giving said member simultaneous movement with the platen, sheet-controlled means for controlling the action of said friction-clutch mechanism, and means called into operation through the operative member for rendering a part or parts of the typewriter mechanism inoperative for use.
21. In a typewriting machine, in combination, a platen, a revolute member, indicating means called into operation through said member, frictional means for causing said member to move with the platen, and a sheet-controlled stop holding said member in a constant starting position while the platen is turned forwardly but permitting an unobstructed movement of the member in a backing-up movement of the platen.
22. In a typewriting machine, in combination, a platen, paper-feeler means, a revolute member actuated from the platen under the control of said paper-feeler means, and a series of indices angularly adjustable upon said member.
23. In a typewriting machine, in combination, a platen, a platen-connected detaining member, indicating means called into operation through said member, a sheet-controlled stop, and a positioning spring for returning said stop into operative position effective for detaining said member.
24. In a typewriting machine, in combination, a platen, a paper-feeler, indicating means controlled by the paper-feeler, means acting to press said paper-feeler toward the paper-path, and a spring acting against the force of the said means.
25. In a typewriting machine, in combination, a platen, a paper-feeler, an operative member actuated from the platen under the control of said paper-feeler, indicating means called into action through said member, and a spring adapted to subtract from the pressure of such paper-feeler upon the sheet.
26. In a typewriting machine, in combination, a platen, a detainable member moving simultaneously with the platen, indicating means called into operation through said member, sheet-controlled means for controlling the movement of said member, and pressure-controlling means for altering the force with which said member presses against said sheet-controlled means.
27. In a typewriting machine, in combination, a platen, a detainable member moving simultaneously with the platen, indicating means called into operation through said member, sheet-controlled means for controlling the movement of said member, the carriage frame, and a pressure-controlling element on said frame for altering the force with which said member presses against said sheet-controlled means.
28. In a typewriting machine, in combination, a platen, a carriage frame, a detaining element on said frame, a sheet-controlled stop, and a detainable member moving simultaneously with the platen and having projecting elements thereon one of which is adapted to coöperate with said stop and the other with said detaining element, and indicating means called into operation through said member.
29. In a typewriting machine, in combination, a platen, an operative member, indicating means called into operation through said member, the carriage frame, a fixed detaining element on said frame, means coöoperating with said detaining element for giving said member a constant starting position, and sheet-controlled means for giving said member simultaneous movement with the platen from said starting position.
30. In a typewriting machine, in combination, a platen, an operative member, printing instrumentalities, means controlled by the operative member for rendering the printing instrumentalities inoperative for use, frictional driving means for giving the said member simultaneous movement with the platen, and means for controlling the said movement, including a sheet-controlled movable stop.
31. In a typewriting machine, in combination, a platen, an operative member,

printing instrumentalities, means called into operation through the operative member for rendering the printing instrumentalities inoperative for use, frictional driving means for giving said member simultaneous movement with the platen, and means for controlling the said movement,

including a friction-opening member and a sheet-controlled movable stop for the friction-opening member.

WILLIAM J. NEIDIG.
